SHOE SUPPORTING JACK

Alfred R. Morrill, Beverly, Mass., assignor to
 United Shoe Machinery Corporation, Paterson,
 N. J., a corporation of New Jersey

Application January 9, 1932, Serial No. 585,764

23 Claims. (Cl. 12—127)

The present invention relates to machines for use in the manufacture of shoes, and more particularly to an improved jack for supporting a shoe in a machine, of the type in which the shoe and the means for operating on the shoe are automatically moved relatively to transfer the point of operation along the shoe and in which the relative position of the shoe and the operating means is automatically changed as the point of operation is transferred along the shoe to present the shoe properly to the operating means.

In machines of the type above referred to, the position of the shoe during the operation thereon is controlled by mechanism acting on the jack and imparting to the jack at predetermined times during the operation, movements predetermined as to direction and extent. Such predetermined movements are imparted to the jack not only during the principal operation on the shoe as, for instance, the inseam sewing operation, but also after the principal operation has been finished, to position the shoe for an auxiliary operation or operations and to move the shoe away from the operating devices and return it to its original position. For the successful operation of these machines it is necessary that the shoe to be operated upon be located accurately in predetermined position with relation to the jack and, for this reason, and on account of the uniform and predetermined movements necessarily imparted to the jack, it has been considered necessary heretofore to supply specially prepared lasts for use in the machines, having certain of their dimensions uniform and predetermined, particularly as to the height of the last and the location of the pin hole for receiving the last pin of the jack.

Ordinary commercial lasts vary considerably in the location and depth of the spindle hole and also vary in depth and in other particulars so that their use heretofore in machines of the type above referred to, has been unsatisfactory and impractical.

An object of the present invention is to provide a jack for use in the type of machine, above referred to, on which shoes supported on ordinary commercial lasts may be secured uniformly in predetermined position so as to be manipulated and presented properly to the operating devices of the machine.

With this and other objects in view, a feature of the invention contemplates the provision in a shoe supporting jack having a toe rest, of novel and improved shoe securing means including a heel gage for determining the position of the bottom surface of the shoe with respect to the toe

rest by direct contact with the bottom of the heel portion. Broadly considered, this feature of the invention contemplates the provision of any suitable means cooperating with the heel gage for securing the shoe on the jack. In the construction hereinafter described, means are provided for forcing the shoe upwardly against the heel gage, this means comprising a last engaging member in the form of a heel post provided with a pin to enter the last pin hole of the last and arranged to engage the top surface of the last. In its preferred form, this feature of the invention also contemplates providing the heel gage with a surface for engaging the end of the shoe and mounting the heel gage so that it is movable toward and from the toe rest to locate the shoe regardless of size longitudinally of the jack. The mechanism for securing the shoe in place may be actuated either automatically or manually, but in the illustrated embodiment of the invention this mechanism comprises a manually operable jacking lever mounted on a cam shaft which, when operated, first acts to lock the heel gage in position and then to force the heel post upwardly toward the heel gage.

In previous machines of the type in which the shoe is fed or the positioning movements controlled at least in part by the machine, manually adjustable toe gages were provided upon the toe rest of the jack in order to fit the forms of different styles or sizes of shoes. According to another feature of the present invention, means are provided for automatically adjusting the gages for centering the toe of the shoe laterally of the jack. The toe centering gages are, in the illustrated embodiment, connected together to move in opposite directions with relation to the center line of the jack. A toe end gage may be employed in conjunction with the centering gages to fix more definitely the position of the shoe lengthwise of the jack. Any suitable means may be provided for moving and holding the toe centering gages in position and, in the embodiment hereinafter described, locking means is provided for retaining the centering gages in place subsequent to their adjusting movement, which means is actuated during the jacking operation.

Other features of the invention consist in certain novel constructions, combinations and arrangements of parts, hereinafter described and claimed, the advantages of which will be obvious to those skilled in the art from the following description and drawings in which, Fig. 1 is a view in front elevation of a machine embodying

the invention; Fig. 2 is a view in front elevation on an enlarged scale of a portion of the jack mechanism illustrated in Fig. 1; Fig. 3 is a similar view of the mechanism illustrated in Fig. 2 with a shoe secured in position on the jack; Fig. 4 is a view in end elevation showing the heel positioning mechanism; Fig. 5 is a partial sectional view along the line 5—5 of Fig. 3; Fig. 6 is a plan view on a still greater scale of a portion of the toe support, indicating in dotted lines the relation of a shoe, as supported by the jack; Fig. 7 is a view in vertical section taken along the line 7—7 of Fig. 6; Fig. 8 is a view in elevation of the toe supporting parts in Fig. 6 from the left hand side; and Fig. 9 is a similar view of the parts shown in Fig. 8, illustrating their normal position when no shoe is supported on the jack.

The invention, as illustrated in the drawings, is shown as applied to an automatic welt or turn shoe sewing machine of the same construction and mode of operation, except as hereinafter pointed out, as that described in the United States Patent No. 1,616,714, granted jointly to L. E. Topham and the present applicant, dated February 8, 1927.

The machine comprises sewing mechanism mounted in a frame 2 supported upon the base 4 of the machine, a shoe supporting jack comprising a toe supporting arm 6 rigid with a spindle 8, a jack supporting structure comprising an arm 10 in the forward end of which the lower end of the jack spindle 8 is rotatably mounted by means of a gimbal joint, a support 12 upon which the arm 10 is mounted to swing vertically, a frame 14 pivotally mounted at its lower end in the machine base so as to be capable of swinging about a horizontal axis and upon which the support 12 is mounted so as to swing about a substantially vertical axis, a vertical pattern cam shaft 16 mounted in the machine base carrying a series of cams 18 and a driving and stopping mechanism supported in a frame 20 mounted on the machine base at one side of the frame 2 of the sewing mechanism. The jack supporting structure is such that the jack can rotate about the axis of the spindle 8 and can tip in any direction about the gimbal joint at the lower end of the spindle. During the operation of sewing the inseam of a shoe mounted on the jack, the lower end of the jack spindle is moved forwardly and rearwardly and laterally of the machine and the jack spindle is rotated, so as to maintain the shoe at all times in the proper relation to the sewing devices. These movements are imparted through suitable connections actuated from the cams 18 on the pattern cam shaft 16. The shoe is fed by the feeding devices of the sewing mechanism and also by a feed lever 22 which is actuated from a cam on the pattern cam shaft 16 and which controls the longitudinal position of the shoe in the machine. At the conclusion of the sewing operation, the thread is cut and held, the sewing mechanism is stopped with the needle free of the work, the welt is severed and the jack is moved outwardly away from the sewing devices and rotated reversely to its original position.

In the machine of the patent, the lasted shoe was supported upon the jack by means of a toe rest on the rigid toe supporting arm and by means of a heel post provided with a last pin engaging the pin hole of the last. The height of the rear portion of the bottom of the last from the gimbal joint at the lower end of the jack spindle and the transverse plane of the

bottom of the last were determined solely by the engagement of the last pin with the pin hole of the last and, consequently, in order that a shoe, regardless of its size or style might be located on the jack with its bottom surface in predetermined uniform position, special lasts were used in the machine, uniform and predetermined as to certain of their dimensions and particularly as to the location of the last pin hole and the height of the last.

The jack illustrated in the drawings, as embodying the several features of the present invention, is designed to support an ordinary commercial last in predetermined position on the jack and with its bottom surface at a predetermined height from the pivotal support at the lower end of the jack and in a predetermined plane. To this end, an important feature of the jack consists of a heel gage which, as shown, comprises a pair of fingers 24 extending laterally and downwardly from the upper end of a gage carrying arm 26 pivoted at its lower end at 28 upon a rigid portion of the jack frame. These fingers are constructed and arranged to engage the bottom surface 30 of the heel portion of a lasted shoe 32 supported in the jack and are so located with relation to a toe rest 34 on the toe supporting arm 6 that the bottom surface of the shoe will be in the desired plane longitudinally of the shoe and at the desired distance from the pivot at the lower end of the jack spindle. The fingers are arranged to contact with the bottom surface of the shoe at the edges or at each side of the longitudinal center line of the shoe bottom 30 and thus act to position the shoe bottom in the proper transverse plane when the shoe is held against the fingers. The gage carrying arm 26 is movable towards and from the toe rest and, in order to cooperate with the toe rest in locating the shoe longitudinally in the jack, is provided with a vertical surface 36 to engage the heel end of the shoe.

The means illustrated in the drawings for forcing the shoe upwardly against the heel gage comprises a heel post 38 provided at its upper end with a short projection 40 adapted to enter the pin hole 42 of the last. The heel post 38 is mounted in the jack so as to be vertically movable to force the shoe upwardly against the heel gage by engagement with the top of the last and is also so mounted that its upper end can move longitudinally of the shoe to enter the pin hole of any size of last. As illustrated, the heel post is pivotally mounted at 44 on one end of a lever 46, which lever is fulcrumed for convenience on the pivotal support 28 for the gage carrying arm 26. The heel post 38 can thus move longitudinally of the shoe about its pivotal connection with the lever and can be forced upwardly by a counter-clockwise movement of the lever 46. The pivot 44 between the heel post 38 and the lever 46 being mounted at the toe rest side of the heel gage pivot 28 is so located with relation to the heel gage fingers that any upward movement of the heel post will apply a force to the shoe along a line passing to the rear of the points of contact of the heel gage fingers, thereby tending to tip the shoe about the fingers as a fulcrum and force the toe portion of the shoe downwardly against the toe rest. The projection 40 at the upper end of the heel post 38 is of a size to enter the pin hole of any commercial last and, in view of the fact that the pin hole of a commercial last is located substantially at the center of the top surface of the last, the heel post acts as a means

for centering the heel portion of the last laterally with respect to the jack.

When there is no shoe in the jack, the heel post 38 and the gage carrying arm 26 assume the position indicated in Fig. 2, both being in a position nearer the toe rest than when the smallest size shoe to be operated upon is in the jack. The gage carrying arm 26 is yieldingly held in this position by a spring 48 attached at one end 10 to the rigid toe supporting arm 6 of the jack, and at the other end to a pin 50 in a projection 52 from the lower portion of the gage carrying arm. The movement of the gage carrying arm under the force of the spring 48 is limited by the engagement of a stop projection 54 formed on the forward end of the arm 52 with the rigid toe supporting arm 6 of the jack frame. The heel post 38 is yieldingly held in the position indicated in Fig. 2 by means of a spring 56 stretched between a pin on the lever 46 and a lug 58 on the lower end of the heel post below its pivotal connection with the lever. The movement of the heel post under the force of this spring is limited by the engagement of the post with the pin 50. With 20 the parts in the position illustrated in Fig. 2, with no shoe in the jack, the heel post 38 is also held yieldingly in raised position by means of a spring 60 stretched between the inner end of the lever 46 and the pin 50, the movement of the lever under the force of the spring being limited by the engagement of stop surfaces 62, 64, formed on the lever and on the forwardly projecting portion 52 of the gage carrying arm 26, respectively.

In the illustrated construction displacement of the shoe on the jack is prevented by locking the gage carrying arm in position and then applying an additional force to the heel post. At the outer end of the projection 52 of the heel gage carrying arm 26 there is provided a sliding and swinging pawl 66 arranged to engage one of a series of rack teeth formed on a rack plate 68 mounted in the toe supporting arm 6 near the toe rest. The forward end of the pawl is formed with a slot through which a pin 70, mounted in lugs at the end of the projection from the gage arm passes. The rear end of the pawl 66 is pivotally connected to one arm of a bell crank 72 fulcrumed at 74 on the projection 52 from the heel gage. The other arm of the bell crank 72 is connected by a link 76 to one arm of a second bell crank 78 pivotally mounted in the heel gage arm on a shaft 80. The other end of the bell crank 78 carries a roll 82 which engages a cam 84 on a shaft 86 passing loosely through the heel gage arm and carrying at one end a jacking lever 88 pinned to the shaft. The roll 82 on the bell-crank 78 is maintained in engagement with the cam 84 by a spring 90 attached at one end to a lug on the bell crank, and at the other end to the pin 50 in the projection 52 from the heel gage. This spring also acts in a direction to move the bell crank 72 in a direction to break the toggle formed by one arm of the bell crank and the pawl 66, so as to move the pawl 66 out of engagement with the teeth of the rack plate 68. After the shoe is in position with its heel against the heel gage, a movement of the jacking lever 88 in a clockwise direction moves the pawl 66 into engagement with the teeth on the rack 68, and locks the heel gage against movement. The heel post 38 is then forced upwardly to clamp the heel seat of the shoe against the fingers 24 on the heel gage by a cam 92 mounted on the shaft 86 to which is secured the jacking lever 88. This cam 92 is arranged to bear on the

outwardly extending arm of the lever 46, the arrangement being such that when the jacking lever is moved in a clockwise direction, as above described, the lever 46 is swung on its pivot by the cam 92 in a direction to move the heel post 38 upwardly. The pressure of the heel post 38 against the top of the last also serves to force the toe of the shoe into firmer engagement with the toe rest, tending to tip the shoe downwardly about the fingers on the heel gage arm 26.

According to another feature of the invention, the toe supporting arm 6 of the jack is provided with a number of toe gages 94, 96, and 98 (see Figs. 6 to 9) for contacting with the bulging upper of the lasted shoe on the jack, while leaving the space just above and below the plane of the sole free for operation of the stitch forming devices. The gage 96 is a part of a bracket 100 which is screwed or otherwise firmly attached at the upper end of the toe supporting arm, and serves to limit the movement of the end of the shoe in a lengthwise direction. The gages 94 and 98 are pivotally mounted upon shouldered screws 102 threaded into lugs extending from each side of the toe rest bracket. The screws 102 are divergently disposed with relation to the center line of the jack, so that the gages 94 and 98 are movable laterally through paths inclined toward the heel gage arm, as well as in a direction toward and away from each other. The two gages 94 and 98 are caused to move by equal amounts in order to coordinate their position with relation to the center line of the jack by inter-engaging gear segments 104 and 106 extending from the pivot portions of the gages 94 and 98 respectively. 100 The gage 94 is moved inwardly by a spring 108 stretched between the segment 104 and a pin 110 (see Figs. 2 and 3) fixed in the toe supporting arm of the jack. The force of the spring 108 is transmitted to the segment 106 to move the other 115 gage 98 inwardly. As the shoe is moved toward the toe rest, the toe of the shoe first strikes the movable toe gages 94 and 98, causing them to be spread apart by equal amounts until the shoe is brought to rest against the end gage 96. These 120 gages thus act under the influence of the spring 108 and the gear segments 104 and 106 to center the toe of the shoe on the jack, and are effective regardless of size or style of shoe.

The centering gages are locked in adjusted position by a latch 112 pivoted at 114 in a slot formed in the bracket 100. The gear segment 106 is provided with a series of teeth 116 cooperating with the latch to lock the centering gages against movement when the latch is moved into engagement therewith. This takes place during the time when the shoe is being jacked, and in the present construction, is produced by the movement of a platen 118 extending from the pivot 114 and attached to the latch in a suitable position to be operated by the toe of a shoe in forcing it downwardly against the toe rest. The latch is normally separated from the teeth on the segment 116 by a spring 120 compressed between the platen 118 and the toe rest. The lowered position of the platen may be regulated by an adjusting screw 122 threaded into the bracket 100 beneath the outer end of the platen. For convenience in construction, a socket 124 (see Figs. 1, 2, and 3) for connecting the end of the jack feeding lever 22 is also attached to the bracket 100 on which the toe gages are mounted.

The nature and scope of the invention having been indicated, and a construction embodying the

several features of the invention having been specifically described, what is claimed is:

1. A shoe supporting jack having, in combination, a rigid frame portion, a fixed toe rest on said frame, a heel gage movable on the frame toward and away from the toe rest, fingers provided on the heel gage for positioning a lasted shoe in said jack with its toe supported in the toe rest and with the bottom of the shoe at opposite sides of the center line thereof abutting the heel gage fingers, and means for clamping the shoe against the heel gage while permitting the shoe to be tipped transversely into a predetermined plane by the engagement of the bottom 80 of the shoe with said fingers. 85
2. A shoe supporting jack having, in combination, a rigid frame portion, a fixed toe rest on the frame, shoe securing means including an arm pivoted to the frame to swing toward and away 20 from the toe rest, having a surface for positioning a lasted shoe lengthwise in said jack with the toe of the shoe against the toe rest and having a gaging element for positioning the bottom surface of the heel portion in a predetermined plane 25 transversely of the shoe and at a fixed elevation with respect to the toe rest, and a last engaging member comprising a projection to enter the last pin hole of the last and permit the shoe to be tipped transversely by the engagement of the bottom 30 surface of the heel portion of the shoe with said gaging element, said last engaging member being mounted on the frame to move toward and from the toe rest and upwardly and downwardly with respect to the gaging element of said 35 positioning arm. 90
3. A shoe supporting jack having, in combination, a rigid frame portion, a fixed toe rest on the frame, an arm pivoted to the frame to swing toward and away from the toe rest, having a surface for engaging the end of a lasted shoe and having a gaging element for positioning the bottom surface of the heel portion at a fixed elevation with respect to the toe rest, a last engaging member comprising a projection to enter the last 40 pin hole of the last, mounted on the frame to move toward and from the toe rest and upwardly with respect to the gaging element of the positioning arm, and resilient means for actuating the positioning arm to force the shoe lengthwise 45 toward the toe rest and for actuating the last engaging member upwardly. 95
4. A shoe supporting jack having, in combination, a rigid frame portion, a fixed toe rest on the frame, an arm pivoted to the frame to swing toward and away from the toe rest, having a surface for engaging the end of a lasted shoe and having a gaging element for positioning the bottom surface of the heel portion at a fixed elevation with respect to the toe rest, a last engaging member comprising a projection to enter the last pin hole of the last, mounted on the frame to move toward and from the toe rest and upwardly with respect to the gaging element of the positioning arm, resilient means for actuating the positioning arm to force the shoe lengthwise toward the toe rest and for moving the last engaging member upwardly, a jacking lever fulcrumed in said frame, and connections operated by the jacking lever actuatable for locking the positioning arm and for tipping the shoe about the heel gage as a fulcrum to clamp the toe of the shoe against the toe rest. 100
5. A shoe supporting jack having, in combination, a rigid frame portion, a fixed toe rest on said frame, a heel gage movable on the frame 105 toward and away from the toe rest for positioning a lasted shoe in said jack with its toe supported in the toe rest and with the bottom surface of its heel portion abutting the heel gage, means for moving the shoe upwardly against the heel gage, and resilient means connected between the heel gage and frame for maintaining the toe of the shoe against the toe rest. 110
6. A shoe supporting jack having, in combination, a rigid frame portion, a fixed toe rest on said frame, toe centering gages on said toe rest for engaging the sides of the toe of a lasted shoe, a heel gage movable on the frame toward and away from the toe rest for positioning the shoe in said jack with its toe supported between said toe gages on the toe rest and with the bottom surface of its heel portion abutting the heel gage, and means for moving the shoe upwardly against the heel gage and for maintaining the toe of the shoe in position between the toe gages. 115
7. A shoe supporting jack having, in combination, a rigid frame portion, a toe rest on the frame, laterally movable toe gages for centering a lasted shoe on said toe rest, connections between said toe gages for coordinating the lateral movement thereof relative to the toe rest, and resilient means for pressing said toe gages against the bulging upper of the shoe being positioned on the toe rest. 120
8. A shoe supporting jack having, in combination, a rigid frame portion, a toe rest on the frame, toe centering gages movable laterally by the toe of a lasted shoe being positioned on said toe rest, connections between said toe gages for coordinating the lateral movement thereof relative to the toe rest, and means actuated in positioning the shoe on the jack for locking the toe gages against relative movement. 125
9. A shoe supporting jack having, in combination, a rigid frame portion, a toe rest on the frame, toe centering gages movable laterally by the toe of a lasted shoe being positioned on said toe rest, connections between the toe gages for coordinating the lateral movement thereof relative to the toe rest, a platen for supporting the shoe 130 on the toe rest, and means connected to the platen and actuated by pressure of the shoe against the platen for locking the toe gages against relative movement. 135
10. A shoe supporting jack having, in combination, a rigid frame portion, a toe rest on the frame, fixed end and movable centering toe gages acting on the bulging upper of a lasted shoe on the toe rest, connections between said toe centering gages for coordinating the movement thereof relative 140 to the toe rest, resilient means for pressing said toe gages against the bulging upper of the shoe being positioned on the toe rest, and means for forcing the shoe lengthwise against the end gage between the toe centering gages and downwardly against the toe rest. 145
11. A shoe supporting jack having, in combination, a rigid frame portion, a toe rest on the frame, fixed end and movable toe gages for centering a lasted shoe on said toe rest, connections arranged to coordinate the movement of the toe gages in opposite directions relative to the toe rest, a platen for supporting the shoe on the toe rest, and means connected to the platen and actuated by the pressure of the shoe against the platen 150 for locking the toe gages against relative movement. 155
12. A shoe supporting jack having, in combination, a rigid frame portion, a toe rest on the frame, fixed end and movable toe gages for centering a 160

- lasted shoe on said toe rest, connections arranged to coordinate the movement of the toe gages in opposite directions relative to the toe rest, a platen for supporting the shoe on the jack, a 5 latch connected to the platen and actuated by the pressure of the shoe against the platen for locking the toe gages against relative movement, and means for forcing the shoe lengthwise against the end gage, between the toe gages and downwardly against the platen to lock the gages on the 10 toe rest. 13. A shoe supporting jack having, in combination, a rigid frame portion, a fixed toe rest on said frame, laterally movable toe gages for centering a lasted shoe on said toe rest, connections 15 between said toe gages for coordinating the lateral movement thereof relative to the toe rest, a heel gage movable on the frame toward and away from the toe rest for positioning the shoe in said jack with its toe supported between the 20 toe gages, locking means on the toe rest for retaining the toe gages against relative movement, and means acting with the heel gage for forcing the shoe into a central position against the toe 25 gages and then against the locking means on the toe rest to lock the toe gages. 14. A shoe supporting jack having, in combination, a jack frame, a toe rest on the frame, laterally movable toe gages for centering a lasted shoe 30 on said toe rest, connections between the toe gages to coordinate the movement thereof in opposite directions relative to the toe rest, a latch mounted in the toe rest to be actuated in positioning the shoe in the jack, a ratchet formed on the toe 35 gage, connections adapted to be engaged by the latch for retaining the toe gages in locked position against the shoe, means for positioning the heel portion of the shoe at a suitable elevation to adjust the toe gages against the bulging upper 40 of the shoe, and mechanism for forcing the shoe lengthwise and downwardly against the toe rest and the toe gages. 15. A shoe supporting jack having, in combination, a jack frame, a toe rest on the frame, laterally 45 movable toe gages for centering a lasted shoe on said toe rest, connections arranged to coordinate the movement of the toe gages in opposite directions relative to the toe rest, a latch having a horizontal extension arranged to be depressed by the toe of a lasted shoe on the toe rest, a ratchet 50 formed on the toe gage connections and adapted to be engaged by the latch for locking the toe gages in position while the latch extension is depressed by the shoe, means for positioning the heel portion of the shoe at suitable elevation to 55 adjust the toe gages against the toe of the shoe, and means for forcing the shoe against the latch extension to lock the toe gages in adjusted position. 16. A shoe supporting jack having, in combination, a rigid frame portion, a fixed toe rest on said frame, a heel gage movable on the frame toward and away from the toe rest for positioning a lasted shoe in said jack with its toe supported in said toe rest and with the bottom surface of 60 its heel portion abutting the heel gage, a heel supporting post mounted in said frame to move independently of the heel gage towards and from the toe rest, and means for moving said post bodily in a direction to force the shoe against the heel gage and tip the shoe with relation to the post about the heel gage as a fulcrum to clamp the toe of the shoe against the toe rest. 17. A shoe supporting jack having, in combination, a rigid frame portion, a fixed toe rest 65 on said frame, shoe securing means including a heel gage for positioning a lasted shoe in said jack with its toe supported in said toe rest and with the bottom surface of its heel portion abutting the heel gage and a heel supporting post, a lever on which the heel supporting post is mounted, and means acting on the lever to apply an upward force to the shoe along a line passing to the rear of the point of contact of the shoe bottom with the heel gage. 18. A shoe supporting jack having, in combination, a rigid frame portion, a fixed toe rest on said frame, shoe securing means including a heel gage pivoted on the frame for positioning a lasted shoe in said jack with its toe supported in said toe 80 rest and with the bottom surface of its heel portion abutting the heel gage and a heel supporting post, a lever pivoted concentrically with the point of connection of the heel gage with the frame and arranged to carry the heel supporting post, and means acting on the lever to apply an upward force to the shoe along a line passing to the rear of the point of contact of the shoe bottom with the heel gage. 19. A shoe supporting jack having, in combination, a rigid frame portion, a fixed toe rest on said frame, shoe securing means including a heel gage pivoted on the frame for positioning a lasted shoe in said jack with its toe supported in said toe 85 rest and with the bottom surface of its heel portion abutting the heel gage and a heel supporting post, a lever pivoted on the frame to carry the heel supporting post, a jacking lever mounted on the heel gage, and connections between the jacking lever and the heel post carrying lever 90 acting when the jacking lever is operated to apply an upward force to the shoe along a line passing to the rear of the point of contact of the shoe bottom with the heel gage. 20. A shoe supporting jack having, in combination, a rigid frame portion, a fixed toe rest on said frame, shoe securing means including a heel gage pivoted on the frame for positioning a lasted shoe in said jack with its toe supported in said toe 95 rest and with the bottom surface of its heel portion abutting the heel gage and a heel supporting post, a lever pivoted on the frame to carry the heel supporting post, a jacking lever mounted on the heel gage, a cam engaging the heel post carrying lever 100 acting when the jacking lever is operated to apply an upward force to the shoe along a line passing to the rear of the point of contact of the shoe bottom with the heel gage. 21. A shoe supporting jack having, in combination, a rigid frame portion, a fixed toe rest on said frame, shoe securing means including a heel gage for positioning a lasted shoe in said jack with its toe supported in said toe rest and with the bottom surface of its heel portion abutting the heel gage and a heel supporting post, a cam 110 shaft, a jacking lever on the shaft, and a lever pivoted on the frame to carry the heel supporting post and arranged for actuation by the cam shaft when the jacking lever is operated to cause the heel post to move upwardly relative to the heel gage. 22. A shoe supporting jack having, in combination, a rigid frame portion, a fixed toe rest on said frame, shoe sewing means including a heel gage for positioning a lasted shoe in said jack with its toe supported in said toe rest and with the bottom surface of its heel portion abutting the heel gage and a heel supporting post, a cam 115 shaft, a jacking lever on the shaft, a lever pivoted on the frame to carry the heel supporting post, means for locking the heel gage in fixed 120 position, and means for moving the heel post upwardly relative to the heel gage. 23. A shoe supporting jack having, in combination, a rigid frame portion, a fixed toe rest on said frame, shoe sewing means including a heel gage for positioning a lasted shoe in said jack with its toe supported in said toe rest and with the bottom surface of its heel portion abutting the heel gage and a heel supporting post, a cam 125 shaft, a jacking lever on the shaft, a lever pivoted on the frame to carry the heel supporting post, means for locking the heel gage in fixed 130 position, and means for moving the heel post upwardly relative to the heel gage. 24. A shoe supporting jack having, in combination, a rigid frame portion, a fixed toe rest on said frame, shoe sewing means including a heel gage for positioning a lasted shoe in said jack with its toe supported in said toe rest and with the bottom surface of its heel portion abutting the heel gage and a heel supporting post, a cam 135 shaft, a jacking lever on the shaft, a lever pivoted on the frame to carry the heel supporting post, means for locking the heel gage in fixed 140 position, and means for moving the heel post upwardly relative to the heel gage. 25. A shoe supporting jack having, in combination, a rigid frame portion, a fixed toe rest on said frame, shoe sewing means including a heel gage for positioning a lasted shoe in said jack with its toe supported in said toe rest and with the bottom surface of its heel portion abutting the heel gage and a heel supporting post, a cam 145 shaft, a jacking lever on the shaft, a lever pivoted on the frame to carry the heel supporting post, means for locking the heel gage in fixed 150 position, and means for moving the heel post upwardly relative to the heel gage.

position relative to the toe rest, and connections operated by the cam shaft for locking the heel gage and for thereafter moving the heel post upwardly relative to the heel gage to clamp the shoe in the jack.

23. A shoe supporting jack having, in combination, a rigid frame portion, a fixed toe rest on the frame, a heel gage movable toward and away from the toe rest having a surface for positioning a lasted shoe lengthwise in said jack with

the toe of the shoe against the toe rest, a gaging element for positioning the bottom surface of the heel portion in a predetermined plane transversely of the shoe and at a fixed elevation with respect to the toe rest, and a last engaging member comprising a projection to enter the last pin hole of the last mounted on the frame to move toward and from the toe rest and upwardly and downwardly with respect to said gaging element.
